ROADBED SIMULATING ATTACHMENT FOR
RAILROAD TRACKS

Raymond E. Smith, Hamden, and Maurice H. Romer, East Haven, Conn., assignors to The A. C. Gilbert Company, New Haven, Conn., a corporation of Maryland

Application March 9, 1950, Serial No. 148,596

7 Claims. (Cl. 238—10)

1

This invention relates to tracks for toy railroads and particularly to improved track bed units preferably constructed so that conventional toy track rail sections may be used either with or without the supplementary bed units of these improvements.

In toy railroads it has been customary to unite laterally spaced toy rails into a rigid skeleton track section by means of crossties or sleepers transversely underlying the rails and fixed thereto. Such crossties in toy railroads are usually spaced for cheapness and simplicity considerably farther apart lengthwise of the rails in proportion to the gauge of the track than are the wooden crossties or sleepers in real railroad construction. In household use such toy track sections commonly rest upon a smooth table top or polished floor and a plurality of them, some straight and some curved, are joined together end-to-end to make up various layouts of a toy track often including sidings or dead-ended spur tracks. The latter in particular are subject to accidental displacement from their proper position, having no means at the dead end for staying them in relation to the surface on which they rest.

Toy track sections have been proposed of more realistic appearance than the conventional kind described above and have included toy roadbed structure of surface contour intended to simulate the tops of dummy sleepers. But such roadbed simulating structures as heretofore proposed have taken the place of actual crossties or sleepers, the toy rails being held spaced by and permanently mounted separately and directly on molded slabs of stiff material contoured to represent the roadbed.

It is an object of the present improvements to provide a mat adapted to serve as a removable base for conventional toy track sections of the skeleton style which mat faithfully simulates or is strongly suggestive of a roadbed preferably ballasted by crushed rock and having sleepers embedded therein. Conventional track section of the skeleton kind including crossties underlying the rails can be assembled with the bed structure of these improvements in such manner that at least part of the crossties are sunk below the top surface of the bed structure and preferably removably embedded therein to such depth that their top surfaces alternate with and lie in coplanar relation to the simulated top surfaces of dummy sleepers configured on the top surface of the bed structure. The invention aims to give to the resulting bed equipped con-

2

ventional track section the appearance of rails supported by like sleepers that are located as closely together in proportion to the gauge of the track as in real railroad construction.

5 A further object is to provide an improved toy roadbed unit so composed that it can be assembled structurally with the crossties of a conventional toy skeleton track section without the use of extraneous fasteners or tools of any kind and in a manner to secure the track section and bed unit together simply by fitting the bed structure to the projecting crossties of the track section by finger manipulation.

10 A contributory object is to provide a mat of the character described made of such moderately soft stretchy resilient material that it can be secured removably to the projecting crossties of a conventional toy track section by a "buttoning on" sort of manipulation.

15 A still further object is to construct a toy railroad track section composed of a roadbed simulating body possessing a strong tendency to cling without sliding on any smooth polished support surface and carrying a multiple rail type of metallic toy track unit anchored thereto, the track rails in no part depending on the bed body for their relative fixity.

20 These and other objectives of the invention will appear in greater particular in the following description of a successful embodiment of the invention having reference to the accompanying drawings wherein:

25 Fig. 1 is a perspective view of combined straight and curved toy track units detachably joined end to end and incorporating the present improvements.

30 Fig. 2 shows the flexible bed mat of the straight track unit of Fig. 1 partially separated from the stiff skeleton structure of the conventional toy track section.

35 Fig. 3 is a fragmentary plan view of an end portion of the improved bed mat with the rail and crosstie conventional track section removed therefrom.

40 Fig. 4 is a bottom plan view of the bed mat of Fig. 3.

45 Figs. 5, 6 and 7 are views taken in section on the planes 5—5, 6—6 and 7—7, respectively, in Fig. 3 looking in the directions of the arrows.

50 Fig. 8 is a fragmentary view drawn on an enlarged scale taken in section on the plane 8—8 in Fig. 1 looking in the direction of the arrows.

55 Figs. 9 and 10 show respectively the conventional track section and underlying mat unit of Fig. 2 wholly separated from each other.

Fig. 11 shows the fingers of an operator's hands in the act of "buttoning-on" or peeling off the flexible bed mat with respect to one of the crossties.

Fig. 12 is a perspective view showing a modified configuration of the base mat of the straight track unit in Fig. 1.

Fig. 13 is a plan view of the modified mat in Fig. 12, partially broken away at its crosstie anchoring ends.

Fig. 14 is a view taken in section on the plane 14-14 in Fig. 13, looking in the direction of the arrows.

Fig. 15 is an enlarged view of a fragment of Fig. 14 showing the track section and mat of Fig. 12 in process of being separated.

Fig. 16 is a fragmentary perspective view of the end portion of a still further modified configuration of base mat.

In Figs. 1, 2, and 9, 12 designates in its entirety a conventional toy track section including stiff preferably hollow metallic rails 13 with their usually metallic underlying crossties or sleepers 14, the sheet metal of each of these crossties in usual fashion having struck-up tongues 15 which fold over the base flanges of the rails for securing the latter in fixed relation to the crossties. There may be the usual folded piece of paper or cardboard 16 between the rail flange and the sleeper tongue to electrically insulate these parts from each other. This conventional construction produces a rigid unitary structure of skeleton nature in which form it is generally placed in use in the usual household layouts of toy railroad resting on a table top or floor surface contacted by the crossties 14 which support the track rails 13. Ends of the rails are detachably connected in alignment by a coupling pin 17 fixedly lodged in the hollow end of one rail and removably insertable in the hollow end of the companion rail aligned therewith.

Owing to the unnaturally wide spacing apart of sleepers 14 along the track rails 13, a circuitous course of toy track composed of merely skeleton sections such as 12 fails of realism of resemblance to actual railroad construction wherein the sleepers are much closer together in proportion to the gauge of the track and are usually embedded in coarse gravel or crushed rock to ballast the roadbed. Heretofore when toy track rails have been equipped with bed structure to more faithfully resemble a real railroad track, actual sleepers or crossties such as 14 have been dispensed with and the track rails 13 have been fixedly joined separately and permanently to an underlying bed structure comprising a rigid slab of material having external contours intended to resemble a roadbed.

According to the present improvements there is provided a bed structure in the form of a mat 20 having a series of pseudo crossties or sleepers 21 configured in its upper surface. But the improved mat is made of moderately soft resilient stretchable material such as natural or synthetic rubber, the mat comprising a slab-like body having an external configuration resembling in miniature the ballasted roadbed of a railroad track. In mat 20 there is sunk below its top surface depressed areas such as depressions or rectangular sockets 23 whose side walls 24 are slanted in an undercut manner to produce the profile of dovetail shape most clearly shown in Figs. 5 and 8.

The width of the socket at the depressed

sleeper seating surface 22 equals the maximum overall width of the sleeper at its bottom turned-out edges 26 and the sleeper admitting mouth of the socket has a smaller width equal to the width of the relatively narrow top surface 27 of the sleeper.

Helped by relative thinness of the surrounding walls of the cavity 23 provided by suction cup hollows 19 in the bottom of mat 20 and by the soft resilient property of the material of the mat there is enough yield to the tapering lips 25 which border the tops of sockets 23 so that each localized portion of the length of mat 20 which contains a socket 23 may by temporary distortion of the shape of such socket be "buttoned onto" one of the projecting crossties 14 of the rigid track unit. Such distortion of the soft rubber of the bed structure is easily permitted in the manner illustrated in Fig. 11 whereby the crosstie may be forced into fitting and filling occupancy of the socket as shown in Fig. 8. Thus the bed structure contains and clings firmly and simultaneously to a plurality of the crossties while the tops of the latter are on a common level with the pseudo ties 21 configured in the top surface of the mat.

The bottom of pad 20 is recessed to a shallow extent in surface areas 28 leaving coplanar border ridges 29 of soft rubber adapted to contact with a table top or floor surface on which the mat rests, while the before-mentioned deeper hollows 19 produce a suction cup effect augmenting the natural tendency of the rubber ridges 29 to cling to a smooth support surface on which they rest. Thus the mat as a whole strongly resists accidental sliding displacement from its designed relationship to associated sections of a track layout. The construction described serves effectively to lessen and deaden all "tinny," "rattling" and objectionable metallic sounds which emanate from conventional toy railway tracks when toy trains are operated thereon and the increased realism of sight and sound that results adds greatly to the pleasure of playing with modern toy trains as well as serving effectively to protect the household surfaces on which track systems are commonly laid out.

While the dummy sleepers 21 of the mat configuration in Figs. 1 to 11 of the drawings rise but slightly above the imitative rocky roadbed surface 32 that intervenes between them, such intervening roadbed surface may be depressed to any desired depth to resemble more nearly an unballasted roadbed of gravel wherein more or all of the height of the dummy sleepers upstands from such depressed bed surface. In one such modification shown in Figs. 12 to 15 the sloping external edges 33 of the mat 31 are retained so that there is a continuous marginal border as high as the top surfaces of the crossties extending longitudinally of the mat past both ends of all crossties and integral with the modified dummy sleepers 34 and preferably retaining a surface configuration imitative of crushed rock or gravel.

Figs. 14 and 15 show a possible way of removably attaching mat 31 to the toy track section 12 wherein only each one of the end crossties 14 of the track section has only its outer foot flange 26 removably anchored by an overhanging ledge 35 of the resilient material of the mat in the manner of the slanting side walls 24 of depressions 23. The depressions 36 bordered at one side by ledge 35 are more shallow than depress-

sions 23 in Figs. 1 to 11, and may be bordered at their other sides by simple ridges such as 37. The manner in which an end of mat 31 may be peeled off from the conventional track section is shown in Fig. 15 wherein the ledge 35 resiliently yields to its distorted shape there shown for permitting the departure of flange 26 from the recess 36. It will automatically spring back to the normal position shown in broken lines in Fig. 15 and in full lines in Fig. 14 each time it is thus temporarily distorted for anchoring the crosstie flange 26 or removing it from the mat. There is also stretch in the thin base wall of the mat between ridge 36 and ledge 35 and this enables the crosstie to be fully seated in depression 36.

For even greater simplicity, all dummy sleepers such as 34 may be omitted from configuration of mat in Figs. 12 to 15 and the mat body may instead consist merely of a slab like 31 except channeled lengthwise to the continuous depth of the depressed surfaces 38 which intervene between the dummy sleepers 34.

The tops 21 of the dummy sleepers such as 21 and 34 may be surface covered to exactly duplicate the surface appearance of the crossties 14 if desired.

Fig. 16 illustrates a still further modification of the mat of Figs. 12 to 15, wherein the sloping longitudinal border edges 33' of the mat 31' are on a common level with the tops of ledges 35 and ridges 37, whereby the dummy sleepers 34 together with the crossties appear to stand in the clear to a common height above the intervening top surfaces of the mat which may be coplanar with the said top surfaces of ledges 35 and ridges 37.

When neighboring mat equipped track units are joined together both the rails and the mat ends of the contiguous units meet in a way to avoid any cracks therebetween as is shown to be the case in Fig. 1 where a straight unit incorporating the invention is coupled to a curved unit incorporating the invention, the elements of the curved unit corresponding to elements of the straight unit being designated by the same reference numerals primed. The manner of manipulating the stiff conventional track section and the bendable resilient base mat to "button" the latter onto the former will be clear from Figs. 11 and 15 and this is done before the resulting units are coupled together end to end.

Fastening sockets for the purpose of depressions 23 may take the form of metallic spring expansion sockets of the snap catch kind permanently embedded either as an insert in the body material of the mat or carried by the metallic structure of a conventional track section. In the former case the rails or sleepers will carry the cooperative snap plug of the fastener which enters and clings to the snap socket. In the latter case such snap plug will be carried by the mat.

Countless variations being possible in the configuration of the bed mat herein illustrated for teaching the invention, the appended claims are directed to and intended to cover in addition to the modifications specifically mentioned herein all other modifications coming within the broadest interpretation of the definitions of the invention as recited in the claims.

I claim:

1. As an article of manufacture adapted for removable attachment to a skeleton section of toy track comprising laterally spaced apart toy

track rails fixedly united by structural crossties underlying and spaced apart along the rails, an accessory mat comprising a slab-like body of flexible resilient material having an external configuration resembling in miniature the roadbed of a railroad track including in relief contour on the top surface of the mat a pseudo representation of the top portions of structural spaced apart crossties, said mat containing a plurality of separate spaced apart sockets formed by the material of said body below said top surface of the mat and located between said pseudo crossties, each of said sockets being separately expansible by distortion of said material and normally of shape and size to admit thereto and closely conform to the top portion of only a single one of the crossties.

2. An accessory adapted for ready attachment to and ready removal from spaced apart structural crossties of a section of toy track, comprising, a mat imitative of a toy track roadbed embodying a flexible resilient body of sufficient length to extend along the track past more than two of the structural crossties, said mat containing cavities opening through the top surface thereof spaced apart lengthwise of the mat in positions to admit a single structural crosstie within each of said cavities, and a configuration in relief formed at the top surface of said mat by the material of said body located between said cavities and approximately duplicating in plan the size and shape of the top surface of one of the structural crossties.

3. An accessory adapted for ready attachment to and removal from spaced apart structural crossties of a section of toy track, comprising, a mat imitative of a toy track roadbed embodying a flexible resilient body of sufficient length to extend along the track past more than two of the structural crossties, said mat containing cavities spaced apart lengthwise of the mat and opening through the top surface thereof to form elongate apertures therein, each of said apertures having its length disposed crosswise said body and closely conforming in plan shape and size to the top of an individual structural crosstie, and at least one configuration in relief formed at the top surface of said mat by the material of said body located between said cavities and approximately duplicating in plan the size and shape of said aperture.

4. As an article of manufacture an imitative roadbed accessory as defined in claim 3, in which there are a plurality of spaced apart configurations like the said configuration in relief and the said top surface of the mat is at least as long from aperture to aperture as is the length of the said apertures.

5. As an article of manufacture an imitative roadbed accessory as defined in claim 3, in which the lengthwise extending cross sectional profile of the said mat is of undulating shape comprising coplanar portions of a bottom wall of the mat underlying the said cavities and at least one portion of a top wall of the mat including the said top surface thereof, all of said walls being substantially thinner than the overall thickness of the mat and said top wall portions and bottom wall portion being located at respectively different height levels within the overall thickness of the mat.

6. A kit of separable parts for building toy railroads comprising, a toy track section having rails united by underlying structural crossties spaced therealong, and a mat imitative in minia-

ture of a roadbed adapted for ready attachment to and ready removal from said crossties, embodying a flexible resilient body of sufficient length to extend beneath said rails past more than two of said structural crossties, said mat containing cavities opening through the top surface thereof spaced apart lengthwise of the mat, each of said cavities being of shape and size to admit only one of said structural crossties therewithin, and a configuration formed in relief at the top surface of said mat by the material of said body located between said cavities and approximately duplicating in plan the size and shape of the top surface of one of said structural crossties.

7. As an article of manufacture adapted for removable attachment to a skeleton section of toy track comprising laterally spaced apart toy track rails fixedly united by structural crossties underlying and spaced apart along the rails, an accessory mat comprising a slab-like body having an external configuration resembling in minia-

5
10

ture the roadbed of a railroad track including in relief contour on the top surface of the mat a pseudo representation of the top portions of structural spaced apart crossties, said mat containing a plurality of separate spaced apart sockets formed by the material of said body below said top surface of the mat and located between said pseudo crossties, each of said sockets being of shape and size to admit thereto and closely conform to the top portion of only a single one of the crossties.
